(57) **CLAIM**

The ornamental design for a lighting fixture, as shown and described.

DESCRIPTION

FIG. 1 is a top perspective view of a lighting fixture depicting a new design;

FIG. 2 is a bottom perspective view thereof;

FIG. 3 is a front elevational view thereof;

FIG. 4 is a back elevational view thereof;

FIG. 5 is a left elevational view thereof;

FIG. 6 is a right elevational view thereof;

FIG. 7 is a top plan view thereof; and,

FIG. 8 is a bottom plan view thereof.

The horizontal broken line extending out beyond the perimeter of the bottom surface of the fixture in FIGS. 3-6 is intended to demonstrate environment only and forms no part of the claimed design. The remaining broken line disclosure in the views represents portions of the lighting fixture that form no part of the claimed design.
